UNITED STATES PATENT OFFICE.

FRANK J. VIERLING AND FRED R. BARTHOLOMEW, OF MINNEAPOLIS, MINNESOTA,
ASSIGNORS TO STERLING SPECIALTIES MANUFACTURING COMPANY, OF MINNEAPOLIS, MINNESOTA, A CORPORATION OF MINNESOTA.

PENCIL.

Application filed September 30, 1920. Serial No. 413,708.

To all whom it may concern:

Be it known that we, FRANK J. VIERLING and FRED R. BARTHOLOMEW, are citizens of the United States, residing at Minneapolis, in the county of Hennepin and State of Minnesota, have invented certain new and useful Improvements in Pencils; and we do hereby declare the following to be a full, clear, and exact description of the invention, such as will enable others skilled in the art to which it appertains to make and use the same.

Our invention has for its object to provide an extremely simple and highly efficient pencil, and to this end, the invention consists of the novel devices and combinations of devices hereinafter described and defined in the claims.

In the accompanying drawings, which illustrate the invention, like characters indicate like parts throughout the several views.

Referring to the drawings:

Fig. 1 is a perspective view of the improved pencil;

Fig. 2 is a view principally in longitudinal section taken centrally through the pencil on an enlarged scale;

Fig. 3 is a transverse section taken on the line 3—3 of Fig. 2, on an enlarged scale;

Fig. 4 is a perspective view of the lead feeding mechanism removed from the casing, with some parts broken away and sectioned;

Fig. 5 is a perspective view of the casing with some parts broken away and sectioned;

Fig. 6 is a perspective view of the cap shown in Fig. 2;

Fig. 7 is a perspective view of the lead holder shown in Fig. 2;

Fig. 8 is a modification of the cap shown in Fig. 6; and

Fig. 9 is a modification of the lead holder shown in Fig. 7.

The numeral 10 indicates a cylindrical casing, the lower end of which is contracted to afford a point 11. Upper and lower circumferential internal grooves 12 and 13, respectively, are formed in the casing 10 by pressing the same outward. The upper groove 12 affords a lock groove for the lead feeding mechanism, as will presently appear.

A cap tube 14 is telescoped part way into

the casing 10 and provided with a stop bead 15 and a lock bead 16, both of which are circumferentially extended and formed by pressing said cap tube outward. The stop bead 15 is arranged to engage the upper end of the casing 10 to limit the telescopic movement of the cap tube 14 into the casing 10, and the lock bead 16 is arranged to enter the lock groove 12 and thereby frictionally secure said cap tube in the casing 10.

To permit the lock bead 16 to spring into and out of the lock groove 12, the cap tube 14 is longitudinally split or slotted at 17 so that said cap tube will contract when pushed into or pulled out of the casing 10 and expand when the lock bead 16 is brought into alignment with the lock groove 12. Obvious by spreading the longitudinal edges of the tube 14 at the slot 17 apart, the frictional engagement of the cap tube 14 with the casing 10 may be increased at will. The upper portion of the cap tube 14 is knurled at 18 to afford a finger grip.

A removable cap 19 has screw-threaded engagement with the upper end of the cap tube 14 to close the same. The lower portion of the cap tube 14 is contracted and then extended to afford a sleeve 20 to receive and rigidly hold the upper end of a tubular feed screw 21 on which is mounted a feed nut 22. To prevent the feed nut 22 from making a complete rotation in the casing 10, but allow axial travelling movement thereof on the feed screw 21, there is formed in the casing 10, by pressing the same inward, a longitudinally extended stop rib 23, see Fig. 3. It is, of course, understood that in some instances, it might be desirable to form a plurality of these ribs in the casing 10 as stops for the feed nut 22.

The feed screw 21 is axially located in the casing 10 and its lower end is seated against the internal tapered walls of the casing point 11 to hold the same against lateral movement, see Fig. 2. A longitudinally extended guide slot 24 is formed in the feed screw 21 intermediately of the ends thereof, and which slot also extends part way into the sleeve 20 from the lower end thereof. The upper end of the feed screw 21 is closed and forms a bottom for the cap tube 14,

which cap tube affords a compartment X normally closed by the cap 19 for a supply of extra leads.

Mounted for endwise movement in the feed screw 21 is a tubular lead feeding stem 25 formed, as shown, by folding a single sheet of metal, the upper extremity of which, at the seam, is extended radially outward to afford a blade 26. This blade 26 extends through the guide slot 24 for travelling movement therein and is provided with an intermediate notch 27 to receive the feed nut 22 and thereby connect the lead feeding stem 25 thereto for travelling movement therewith. By extending the blade 26 through the guide slot 24, the lead feeding stem 25 is connected to the feed screw 21 for common rotation therewith but with freedom for endwise travelling movement therein.

The lead feeding tube 25, near its lower end, is notched at 28 at its seam to leave therebelow a pair of spring jaws 29 adapted to frictionally hold a piece of lead Z. At the upper end of the notch 28, a small portion of the lead holding stem 25 is folded into said stem to afford a stop 30 to limit the endwise movement of the lead Z into the lead feeding stem 25.

Obviously, by turning the cap tube 14 in the casing 10, the feed screw 22 may be turned in either direction to thereby impart an endwise movement to the lead Z, either to project or retract the same in the point 11. By drawing outward on the cap tube 14 with sufficient force to cause the lock bead 15 to cam itself out of the lock groove 12 under the contraction of the cap tube 14, the entire lead feeding mechanism may be withdrawn from the casing 10.

To prevent the blade 26 from striking the upper end of the guide slot 21 and thereby bending the same during the receding movement of the lead feeding stem 25, the lower end of the stem 20 is arranged as a stop 20' for the feed nut 22.

The modified cap 31, shown in Fig. 8, is adapted to be screwed into the lead feeding tube 14 the same as the cap 19, and has attached to its screw-threaded end an eraser 32. To use the eraser 32, the cap 31 may be unscrewed from the cap tube 14, inverted and the top thereof inserted into said cap tube. The two circumferential surfaces 33, on top of the cap 31, are of the same diameter and of such size as to tightly fit within the casing 10 and frictionally hold said cap in position while the eraser 32 is being used.

Referring now to the modified form of lead holder shown in Fig. 9, the same is formed from a closed tube 34, and a notched blade 35, for the feed nut 22, is formed on the upper end of a rod 36 which is forced into the tube 34 from the upper end thereof and held in place by friction. The tube 34

is notched just below the lower end of the rod 36, to leave therebelow a pair of lead holding jaws 38. In this form of lead holder, the lower end of the rod 36 affords a stop for the lead Z.

It is evident that the casing 10 shown in detail in Fig. 5 constitutes an outer casing; that the cap tube 14 and tubular feed screw 21 combined form an inner casing; and that, when the device shown in Fig. 9 is inserted within the tubular portion 21 of the inner casing, that the device then comprises inner and outer telescoped casings, a stem centrally supported in the inner end of the inner casing and projecting toward the outer end of the outer casing, and a sleeve surrounding the stem and projecting beyond the same, the projecting portion of said sleeve forming a lead holder.

What we claim is:

1. A pencil comprising a casing, a tube telescoped into the casing and having movable frictional engagement therewith, said tube having a longitudinal slot terminating short of its ends which permits circumferential contraction and expansion of the tube, lead-engaging means on the tube, and a circumferential lock groove and a projection extending therein, one of which is formed in the casing and the other of which is formed in the tube, said lock groove and projection being located intermediate of the ends of the slot in the tube.

2. A pencil comprising a casing, a tubular feed screw mounted in the casing and having a longitudinal guide slot, a feed nut on the feed screw, means for holding the feed nut against rotation in the casing but with freedom for axial travelling movement thereon, a lead feeding device mounted in the feed screw and having a blade working in the guide slot, interlocked with the feed nut and extending thereabove, and a stop arranged to be engaged by the feed nut to prevent said blade from coming in contact with the upper end of the guide slot.

3. A pencil comprising inner and outer telescoping members relatively longitudinally movable, said inner member having a longitudinal slot terminating short of its ends, a stop on one of said members engageable with the other member to limit telescopic movement of the two members, a stem centrally disposed in the inner member, and a sleeve surrounding said stem and having a portion projecting beyond said stem, said sleeve portion forming a lead holder.

4. A pencil comprising inner and outer telescoping members relatively longitudinally movable, said inner member having a longitudinal slot terminating short of its ends, a stop on one of said members engageable with the other member to limit telescopic movement of the two members, a stem centrally disposed in the inner mem-

ber, and a sleeve surrounding said stem, permanently secured thereto and having a portion projecting beyond said stem, said sleeve portion forming a lead holder.

5. A pencil comprising inner and outer telescoping casings relatively longitudinally movable, a stem centrally supported in the inner end of the inner casing and projecting toward the outer end of the outer

casing, and a sleeve surrounding said stem and projecting beyond the same, the projecting portion of said sleeve forming a lead holder.

In testimony whereof we affix our signatures.

FRANK J. VIERLING.

FRED R. BARTHOLOMEW.
